UNITED STATES PATENT OFFICE.

HENRY O. HALL, OF ST. PAUL, MINNESOTA.

EXTENSION-TABLE SLIDE.

SPECIFICATION forming part of Letters Patent No. 359,782, dated March 22, 1887.

Application filed July 22, 1886. Serial No. 209,282. (No model.)

To all whom it may concern:

Be it known that I, HENRY O. HALL, a citizen of the United States, residing at St. Paul, in the county of Ramsey and State of Minnesota, have invented certain Improvements in Extension-Table Slides, of which the following is a specification.

This invention relates to improvements in that class of extension-tables in which extension-bars are used having grooves upon their upper and lower edges, with metallic plates or slides that are secured to the top and bottom of both bars, the plates that are secured to each bar projecting over the other bar and being provided with ribs that travel in grooves therein. An example of this class of slides is shown in the patent to Elisha Mets, No. 36,496, granted September 16, 1862.

Heretofore it has been customary to secure the metal plates to the rails by screws that were passed through each plate near one edge thereof. This manner of securing the plates has always been open to objections, as the screws could not be set into the wood with sufficient accuracy to bring them into corresponding positions upon the two edges of the rail, and one plate would often cant or twist in one direction and the other in another. Moreover, the plates were held by short screws only, and they were placed so near the edge of the rail as to frequently split the wood, thus making the slide insecure and liable to get out of place. Again, in the old slide the screws were placed close to one of the ribs upon the plate, and as there was no bearing for the plate beyond the rib, and the groove was often deeper than the rib, the edge of the plate was often drawn into the groove, throwing the other edge outward, so that the plate could not bear firmly on the bar. I seek to overcome these objections by providing the slides with a common securing means that draws them firmly against the top and bottom of the bar. I also provide the slide with a bearing-flange that extends beyond the edge of the slide, and keeps it from being brought unevenly against the bar.

In the accompanying drawings, forming part of this specification, Figure 1 is a plan of two of the extension-bars with the slides secured thereto. Fig. 2 is a section on line X X of Fig. 1. Fig. 3 is a section on line Y Y of Fig. 1,

showing the plates held by screws. Fig. 4 is an under side view of one of the metal plates. Fig. 5 is a similar view of a plate having two bearing-flanges. Fig. 6 is an end view of the plate.

The bars A are of ordinary construction. They are provided upon the top and bottom, near their edges, with the longitudinal grooves B. The short metallic plates C are placed on the top and bottom of each bar, and project beyond its edge and over the top and bottom of the next bar. Each plate is provided with a rib, D, that rests in the groove B, thereby holding the bars together. A hole is made through the bar, and a bolt is passed through one of the plates, through the bar, and through the other plate, and is provided with a nut, F. By this means both plates are drawn firmly against the bar and held in corresponding positions.

The advantages from this construction are that both plates are equally and firmly drawn against the wood, there is no danger of splitting the wood, and each plate serves as a washer for the bolt, and the two metal plates, therefore, take nearly all the strain off the bar. The bars are preferably recessed, so as to allow the plates to set below their surface.

I prefer to provide each slide with a rib, D', near its opposite edge, and to set this rib into the groove in the bar to which the plate is secured, and to provide a bearing-flange, G, that projects beyond the rib D' and bears upon the wood on the other side of the groove. This flange keeps the edge of the plate from being drawn into the groove. The bolt-hole H is formed in the plate, preferably in about the line of the rib D'. The plate may, if preferred, be provided with more than one flange G, as shown in Fig. 5. The plates having the bearing-flanges G may be secured to the bars by screws E, as shown in Fig. 3; but I prefer to use a single fastening, as described, for both plates.

I am also aware of the patent to May and Hooper, No. 97,209, granted November 23, 1869, and I claim nothing therein shown or described. I make a direct connection between the two metal plates, and the strength of the slide and its weight-carrying power are only limited by the strength of the plate; in other

words, it is equal to the breaking strength of the iron. In the old slides it equals the hold of the wood upon the screw-thread, which would vary materially, according to the density of the wood or its fibrous strength. In the best wood, and that which would have the strongest hold on the screw, it is difficult to drive the screw without boring so near to the size of the screw itself as to reduce the cut of the thread into the wood and so lessen its hold. If the wood were not bored, a large number of screw-heads would be broken, which would involve the taking out of the screw, the reaming of the hole, and the insertion of a new screw. 15 In the former case (as the woods must be bored alike, and as they vary greatly as to strength, toughness, and density) there will be an appreciable percentage of brash pieces, in which, with a hole so bored, the hold of the screw will 20 be merely nominal. With my slide all pieces can be used with equal safety. Moreover, if a screw gives out in the old slide the table will break down, whereas if the plate breaks in my slide, which is the worst that could happen, 25 its running capacity only is destroyed, for the nut on the end of the bolt will hold the parts in position under any test that a table will be put to. The slide with one bolt can be made cheaper than the slide with four screws, (one 30 bolt answering the purpose of that number of screws,) and owing to the greater strength given by the bolt-fastening the sections can be made with less lap, consequently fewer sections to a table, and as a result a cheaper ar-

ticle than heretofore, and at the same time a 35 better one.

I claim as my invention—

1. The combination, with the bar A, having the grooves B, of the plates C, having the ribs D, sliding in the grooves B, and having the 40 bearing-flanges G, extending beyond the edge of the plate, whereby a bearing is provided upon both sides of the groove B on the bar to which the plates are secured, and a bolt passing through both plates and through the bar 45 and clamping the plates upon the bar in corresponding positions.

2. The combination, with the bar A, having the grooves B, of the plates C, secured upon the top and bottom of said bar and having the ribs 50 D, and the bearing-flange G, extending beyond the edge of the plate, whereby a bearing is provided upon both sides of the groove B, substantially as set forth.

3. As a new article of manufacture, the extension-table slide consisting of the metallic plate C, having at its opposite edges upon the same side the projecting ribs D D', and the bearing-flanges G at one edge of the plate, with a hole through the plate near the rib D', substantially as described. 55

In testimony whereof I have hereunto set my hand this 23d day of July, 1886.

HENRY O. HALL.

In presence of—

A. C. PAUL,

R. H. SANFORD.
